Nathan F. Mathewson

UNITED STATES PATENT OFFICE.

NATHAN F. MATHEWSON, OF PROVIDENCE, RHODE ISLAND.

WATCH-CHAIN SWIVEL.

Specification of Letters Patent No. 11,133, dated June 20, 1854.

To all whom it may concern:

Be it known that I, NATHAN F. MATHEWSON, of Providence, in the county of Providence and State of Rhode Island, have invented a new and useful Improvement in Watch-Chain Swivels; and I do hereby declare that the following is a full, clear, and exact description of the same, reference being had to the accompanying drawings, 10 making a part of this specification, in which—

Figure 1, exhibits the external form of one of my improved watch chain swivels. Fig. 2, is a vertical central section of the 15 same. Fig. 3, is a horizontal section through the line, x , x , in Fig. 2.

Similar letters of reference in each of the several figures indicate corresponding parts.

My invention has reference to a well known arrangement of swivel hook in which a sliding tube or collar containing a spring is used for locking the hook when closed, and my improvement in said form or kind of hook consists in a novel construction or 25 arrangement of the parts whereby the usual swivel cross joint or joints in the hook are dispensed with, thus economizing the construction and wear or reducing the liability to derangement of the hook, and whereby the 30 hook may be opened or closed quicker and with greater ease and be set so as to remain open without being held so by the finger or hand and without destroying the loop form of the hook thereby affording greater 35 convenience and security in putting on or off the watch.

To enable others to make and use my invention, I will proceed to describe its construction and operation more fully.

40 A, B, represent the loop or hook for receiving the ring of the watch. This loop is divided obliquely at a , as represented—the part, B, being attached to the bottom of the socket, C, and the part, A, has a shank, 45 D, which passes up loosely through a square opening, b , in the center of the bottom of the socket, C, and receives the swivel ring, E, at its upper end, as shown in Fig. 2. The shank, D, is made square, or many 50 sided, at its lower extremity, c , and corresponds to the shape of the opening, b , in the bottom of the socket, C, and when this square, c , fits in the square opening, b , it is impossible for the socket to be turned. It 55 fits thus when the two parts, A, B, are in the position shown in black, in Figs. 1, 2,

and 3. The upper portion, d , of the shank, is made cylindrical, and has the spiral spring, e , placed around it—said spring being arranged between the shoulder, f , and the bottom of the socket, C. By making the shank, D, square at, c , and employing the spiral spring, the socket and movable part, B, of the hook or loop, are prevented from turning or rising of their own accord, 60 after being arranged in proper relation to the stationary part A to form an unbroken loop—the spring serving most effectually for preventing them rising, and for keeping the bottom of the socket against the shoulder, 65 g , of the part, A, of the hook. This spring, however, allows of the socket being raised or moved longitudinally in a direct line, until it is entirely out of contact with the square portion, c , of the shank; and the 70 cylindrical part, d , of the shank, then allows of the socket turning, so as to form an opening in the loop, or rather increase the size of the one formed by raising the socket in a direct line—said opening being formed 75 for the purpose of admitting the ring of the watch.

It should be observed, that when the socket is turned to the position shown in red in Figs. 2, and 3, that the corners of the square 80 opening, b , come opposite the sides of the square, c , of the shank; and consequently, the sides of said opening stand across the corners of the square, and thus the socket is prevented from assuming the position 85 shown in black, until turned by the hand, and the sides of its opening brought in line with the sides of the square, c . The spring serves for keeping the bottom of the socket in rigid contact with the top of the square 90 while it is turned to the position shown in red, and causes it to adjust itself when the sides of the opening, b , are in line with the sides of the square, c . It also holds the two parts, A, B, firmly together, and thereby 95 prevents the escape of the watch.

The sliding tube or collar (C) differently constructed with spring inside for locking the hook and, by sliding the collar upward, unlocking the same is, in itself, as before 100 adverted to, an old device, but, in such previous arrangement, the hook has been cross jointed at its bottom and the sliding collar been provided with a groove or recess for receiving the opening end of the hook. In 105 such an arrangement, much less convenience and security is afforded for putting on and

off the watch, as, in opening, the sliding collar has first to be raised and then the jointed or opening section of the hook turned considerably downward, in which 5 action there is great risk of the watch falling unawares or too abruptly from the widely opened hook and less facility generally afforded for putting on and off the watch than where the hook forms, when open, a tolerably close loop as is the case with my arrangement. Such close loop however formed by the open hook is common to other forms of swivel hooks, but in these, as in the instance more particularly referred to, the one 15 section of the hook is connected to its adjoining part by a cross swivel joint, which, in every instance, is an objectionable mode of construction, not only as involving greater expense at first (and this in making 20 such articles in large quantities is a matter of much import) but as rendering the device more liable to derangement and wear and this is especially the case where the joint is at the bottom of the hook causing wear 25 likewise to the watch-guard rubbing over the rough surface produced by the joint.

By the construction and arrangement I adopt, no cross swivel joint has to be formed in the hook whereby the wear and cost of 30 construction is economized—the small section (B) of the hook being formed out of the same piece as, or otherwise made fast to, the sliding collar (C),—and the hook may be opened with much greater facility and 35 be kept open without applying the finger or hand to the open section (a great convenience in the handling of the watch) while the watch is being put off or on the hook, as, in opening the hook for removal 40 of the watch it is only necessary to slide the collar (C) upward sufficiently far to clear the square shoulder (c) and then to turn

the collar so as to make the recess in its lower end occupy a crosswise or angular position on the square shoulder (c), as represented in red lines in Fig. 3, when the spring in the collar will, by its pressure, firmly hold or keep set the small section (B) in its open position. These are advantages which when combined make the 50 swivel hook much more convenient, perfect in its operation, durable and cheaper of construction.

I do not claim as new, in swivel hooks, the combination of the spring (e) and its 55 inclosing slide or collar (C) for locking and unlocking the hook, as such has before been used; nor yet, merely of itself, making the loop or bow of the hook in separate sections; but

I do claim as both new and useful, and desire to secure by Letters Patent,

Constructing the spring inclosing slide (C) with the smaller or opening section (B) of the loop fast to it and gearing the 65 said slide, by square or angular recess (b) in it and corresponding shaped shoulder (c) on the shank, with the main section of the loop for operation together in the manner specified, whereby the hook is opened and 70 closed with greater facility and the opening section (B) firmly held in its open position without applying the finger or hand thereto and without destroying the loop form of the hook and without employing a 75 cross swivel joint in the loop, as shown and described and by which construction, combination and arrangement numerous advantages as herein specified are obtained and the device generally improved.

NATHAN F. MATHEWSON.
